UNITED STATES PATENT OFFICE.

ALLEN HOUSE, OF PARAGOULD, ARKANSAS.

GUIDE FOR SAWS.

SPECIFICATION forming part of Letters Patent No. 379,165, dated March 6, 1883.

Application filed November 9, 1887. Serial No. 254,694. (No model.)

To all whom it may concern:

Be it known that I, ALLEN HOUSE, a citizen of the United States, residing at Paragould, in the county of Greene and State of 5 Arkansas, have invented a new and useful Improvement in Guides for Saws, of which the following is a specification.

My invention relates to improvements in guides for saws; and it has for its objects the 10 provision of a simple device to be attached to the bed of a sawing-machine, whereby the saw may be guided and held from lateral play.

The invention consists in a device having a slotted plate to be secured to the bed of the 15 machine and a rigid guide-arm which is formed integral with the slotted plate. To one end of the rigid arm is pivoted the end of a movable arm, which is adapted to be raised to a vertical position to allow the saw-blade to be inserted between the free ends of the guide-arms. The movable arm is provided with a lateral wing or stop to bear on the upper side of the rigid arm to support the former in the horizontal or operative position. The free ends of 20 the guide arms are provided with horizontal tapped openings, in which are arranged the adjusting-screws, which bear at their inner ends against opposite sides of the saw.

The invention is described more fully in 25 connection with the accompanying drawings, in which—

Figure 1 is a perspective view of a portion of a sawing-machine with my improved guide applied thereto in the operative position. 30 Fig. 2 is a perspective view of the guide detached from the machine, and showing the movable arm raised in dotted lines, to illustrate its manner of operation. Fig. 3 is a detached perspective view to show the connection between the guide-arms.

Referring to the drawings, in which similar letters of reference denote corresponding parts in all the figures, A designates the bed of the sawing-machine and E designates the saw, 45 which is supported thereon and operated in any ordinary or preferred manner.

C designates the improved guide, of which C' represents the slotted plate having the longitudinal slots E E. The said slotted plate is 50 adapted to bear on any convenient portion of

the bed of the machine adjacent to the saw, and the bolts F F are passed through the slots E E and secured in the bed. It will be seen that the guide C is capable of longitudinal adjustment to suit the size of the saw employed 55 in the machine.

To the outer side of the slotted plate is attached the rigid guide-arm D, (which is preferably, as before stated, formed integral with the slotted plate,) and the said arm is provided 60 at one end with a horizontal tapped opening, d. The opposite end of the arm D is provided on the lower side with a depending eye, E', the opening in which is horizontal.

G designates a movable or swinging guide-arm, which is provided at one end with a horizontal tapped opening, g, aligning with the opening d in the rigid arm, and at the other end with a depending eye, H, having a horizontal opening therein which is adapted to be 70 aligned with the opening in the eye E'.

I designates the pivot-pin, which is passed through the aligned eyes E' H, whereby the movable guide-arm is pivoted to the rigid arm and is capable of vertical movement at the 75 outer or front end.

K L designate adjusting-screws, which are fitted in the tapped openings in the ends of the guide-arms, and wooden plugs k l are arranged in the inner ends of the said screws to 80 bear against opposite sides of the saw. It will be seen that the said adjusting-screws may be screwed in or out to bring the saw into the proper line.

The guide arm D is provided on the upper 85 side at the rear end with a recess, M, and the rear end of the arm G is provided on one side with the laterally-extending wing or stop N, which is adapted to fit snugly in the recess M when the movable arm G is in the horizontal 90 position. It will be seen that when in the horizontal position the arm G is parallel with the arm D.

To place the saw in position it will be seen that it is not necessary to remove the guide; 95 but the movable arm G is simply raised at the outer end and then lowered when the saw has been properly adjusted. When the movable arm is in the horizontal position, it is supported and held thus by the lateral wing or stop N, 100

and it will be seen that there is no necessity for any fastening for the movable arm, as it will be thus held firmly in the operative position.

5 The construction of this device is very simple, enabling it to be very easily and cheaply manufactured, and, being formed in a connected form, it may be attached to any machine without any previous preparation. It is usual to form the guides in several distinct parts, all of which are attached separately to the sawing-machine. It has been my object to provide a device which could be quickly and easily attached to any machine now in use, all the parts of the said device being connected, so that they might be attached at the same time and by the same operation.

Having thus described my invention, I claim—

20 1. The herein-described saw-guide having the slotted plate C', the rigid arm D, secured to the said plate and having the depending horizontal eye E' on the rear end, the movable

arm G, having the depending horizontal eye H on one end to align with the eye E', the pin 25 I, passing through the said aligned eyes, and the lateral wing or stop N on the side of the movable arm to bear on the rigid arm when the said arms are parallel, substantially as and for the purpose specified.

30 2. In a guide for saws, the combination of the slotted plate C', the rigid arm secured thereto and having the recess M in the upper side thereof at the rear end, and the vertically-swinging arm G, hinged to the rear end 35 of the rigid arm and having the lateral wing or stop N to fit in the recess M when the arms D and G are in the operative positions, substantially as described.

In testimony that I claim the foregoing as my own I have hereto affixed my signature in presence of two witnesses.

ALLEN HOUSE.
